(57) **CLAIM**

The ornamental design for a headphone cover, as shown and described.

DESCRIPTION

FIG. 1 is a top perspective view of a headphone cover, showing my new design;

FIG. 2 is a bottom perspective view thereof;

FIG. 3 is a front side view thereof;

FIG. 4 is a back side view thereof;

FIG. 5 is a left side view thereof;

FIG. 6 is a right side view thereof;

FIG. 7 is a top plan view thereof; and,

FIG. 8 is a bottom plan view thereof.

In the drawings, the broken lines are for the purpose of illustrating environment only and form no part of the claimed design.

1 Claim, 3 Drawing Sheets
